(57) **CLAIM**

The ornamental design for a log cover, as shown and described.

DESCRIPTION

FIG. 1 is a top plan view of a log cover showing our new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a perspective view thereof.

The broken lines shown in FIGS. 3, 4, and 6 represent unclaimed features of the design.
